STRATIFIER WITH SUCTION SEPARATION

Theodore F. Garland, Fargo, N. Dak.

Application January 15, 1954, Serial No. 404,318

8 Claims. (Cl. 209—423)

This invention relates to submerged apparatus for cleaning gravel and to the method of removing undesirable intermixed materials therefrom.

Gravel and sand, without impurities intermixed therewith, are extremely hard and durable materials and, if securely bound together as in concrete or the like, produce an extremely hard construction material which is structurally sound. However, foreign materials such as shale, coal or other light-weight, porous materials have little cohesive strength and are subject to scaling, chipping and rapid deterioration. If such materials are intermixed with gravel when the same is used in concrete or the like, the strength of the concrete will be substantially reduced as compared with concrete made with gravel which is free of these impurities. It is, therefore, desirable to remove these undesirable materials from the gravel with which they are mixed.

In the past, iron ore and other gravity-separation equipment preparatory to refining of metals and the like has been used, but all of this equipment is relatively expensive and requires a substantial amount of maintenance and, therefore, is not suitable for gravel which must, of course, sell for a relatively low price. Gravel is also extremely hard and the abrasive action thereof on the equipment requires a relatively high degree of maintenance.

It is, therefore, an object to provide a simple and inexpensive method and apparatus particularly designed for efficiently cleaning gravel products and the like by removing light weight foreign materials therefrom.

Another object of my invention is to provide gravel-cleaning apparatus particularly designed to reduce the harmful and damaging effects of the abrasive action of the gravel and to produce a submerged gravity-type separator constructed to permit low initial cost as well as high efficiency of operation.

It is another object to provide a novel and highly efficient method of cleaning gravel by removing the undesirable light weight intermixed materials therefrom.

Still another object of my invention is to provide in apparatus for separating materials having different specific gravities, a system for separately withdrawing the lighter materials and the heavier materials without running either through a hydraulic pump.

More specifically, it is an object of my invention to provide a gravity separator of the submerged type being particularly adapted for gravel and other abrasive materials and designed to remove solely by siphon action, the light weight layer of accumulated materials without running the same through a hydraulic pump and subsequently removing substantially all of the solid particles from the water, and through the use of a single hydraulic pump, recirculating the water through the system.

A further object of my invention is to provide a novel and highly efficient method of removing light weight foreign materials from gravel or the like by submerging the mixed gravel and lighter materials in a liquid, shak-

ing the submerged mixture to cause the lighter materials to accumulate in a layer above the heavy materials, and removing and discharging the layer of light materials by siphon action, and the method may also include collecting the water discharged with the solid materials, and recirculating the water back into the system.

A still further object of my invention is to provide apparatus for combinatively washing gravel products and the like and separating them from lighter foreign materials mixed therewith.

These and other objects and advantages of my invention will more fully appear from the following description made in connection with the accompanying drawings wherein like reference characters refer to the same parts throughout the several views and in which:

Fig. 1 is a vertical sectional view of my apparatus showing portions thereof in side elevation;

Fig. 2 is a vertical sectional view of my apparatus showing portions thereof in end elevation; and

Fig. 3 is a diagrammatic view of my invention.

One embodiment of my invention, as shown in Figs. 1 through 3, includes a liquid-confining tank 10 being filled with a liquid 11 such as water. The liquid is supplied under pressure to the tank by means of a water supply pipe 12 which has suitable means, such as a float valve 13 connected therewith for maintaining a constant level of water in the tank. The float valve will then stop the filling to prevent the water from running over the top.

A number of separating beds or trays 14 are shiftably mounted in the tank 10 below the level of the water therein. The beds 14 are all connected together and are suspended from the top of said tank by means of supporting arms 15. The separating beds are substantially horizontally disposed in the tank and are vertically spaced along the length of the vertically disposed supporting arms 15. In the form shown, these beds are substantially longer than they are wide, being substantially rectangular, and have a perforate bottom with many small perforations therein which will allow water to pass therethrough but will not allow passage of any of the materials carried by the beds. In the form shown, the beds have an open top and upstanding material-confining side walls.

The supporting arms 15 are swingably mounted at their upper ends on a pivot support 16 which is connected to the moving linkage of a pitman oscillating mechanism designated by letter P in Figs. 1-3, the oscillator being affixed to and mounted on top of the tank 10. The oscillator consists in a rotating shaft 17 powered by an engine or motor (not shown) and a rotating arm 18 affixed to the shaft 17. A link 19 is pivotally connected at one of its ends to arm 18 and is pivotally connected at its other end to crank arm 20. A link or bar 22 pivotally interconnects crank arm 20 and crank arm 21 so as to give crank arms 20 and 21 substantially the same movement as they oscillate respectively about the axes of parallel shafts 23 and 24 to which they are affixed. Lever arms 25 and 26 are also affixed at one of their ends to the shaft 24 and have pivot supports 16 affixed to their other ends. The supporting arms 15 are suspended from pivot supports 16. As the arm 18 rotates with shaft 17, it imparts an oscillatory movement to the crank arms 20 and 21 which move in an arc about the axes of shafts 23 and 24. Lever arms 25 and 26, also being affixed to the shafts 23 and 24, also have an oscillatory movement to the supporting arms 15 affixed to the trays 14 and therefore also impart the oscillatory movement to the beds 14. The beds 14 have an oscillatory movement consisting of a combined vertical movement and a movement longitudinal of the beds.

70

A mixture of size-graded materials that have various specific gravities is supplied to the ingress ends 27 of each of the beds by any suitable means such as by conveying tubes or conduits 28, one of which extends to each of the beds and positioned so that material carried thereby will fall by gravity from the end of the tubes 28 into the ingress ends 27 of the beds 14.

The oscillatory movement of the beds imparted by the pitman oscillator P causes the material supplied thereto to move along the beds away from the ingress ends 27 toward the egress ends 29 of the beds. This oscillating movement of the beds 14 also causes the lighter of the materials which in this instance consists in shale, coal and other foreign material found in natural gravel, to rise in a layer above the heavier materials which consists in gravel and graded silicious metal.

As the materials move in the beds toward the egress end 29 thereof, the layer of lighter materials is picked up and discharged through siphon tubes 30, these being at least one such siphon tube associated with each bed and the egress end thereof. The inlet end of the siphon tubes 30 comprises a housing 31 which is semi-circular in shape and hollow and communicates with the siphon tube 30. The lower end of the housing 31 has an elongated slot or opening therein extending transversely substantially across the width of the beds at the egress end thereof, and is disposed in spaced relation above the bottom of the bed and above the layer of heavy silicious materials moving longitudinally of the bed.

Obviously, the cross sectional interior size of the siphon tubes is necessarily several-fold larger than the size of the largest of the pieces of lighter material to be carried thereby. The siphon tubes 30 extend through the side walls of the tank and extend to their outlet ends which are disposed outside the tank and substantially below the surface elevation of the water in the tank. Each of the siphon tubes 30 have means, such as the adjustable flow nozzles 30a, for regulating the flow of water and solid materials which pass through the tubes.

The difference in the head of water between the surface thereof in the tank and the outlet end of each siphon tube 30 causes water to flow into the inlet housing 31 and through the siphon tube 30. As the water flows into the elongated slot of the housing 31, it passes in close proximity with and through the layer of lighter materials adjacent to the slot in housing 31. The water flowing into the housing 31 picks up and carries with it the upper-layer of lighter materials in the bed and carries this material out of the tank. Obviously, if necessary, there may be more than one siphon tube employed with each of the beds.

After the layer of light materials have been removed from the oscillating bed 14, the layer of heavy materials continues to move toward the egress end of the tray. At the egress end 29 of the beds the heavy materials are spilled over the end thereof and are discharged into a hopper 32 which collects said heavier silicious materials. This heavy material moves downwardly by gravity through the hoppers 32 and through conveying tubes 33. In the form shown, a pair of conveying tubes 33 may be connected to each of said hoppers to carry the heavy materials from the beds to various blending receptacles 34.

Shiftably mounted in each of the hoppers 32 is a gate 35 which forms an obstruction in the hopper at a desired location along the width thereof to direct a certain proportion of the heavy materials falling into the hopper into one conveying tube or another and into one blending receptacle or another. Each of the gates 35 is pivotally mounted in the bottom of the respective hopper and the position of the gate may be controlled by means of control lever 36 which is connected to the gate 35 by means of shaft 37.

Heavy material discharge tubes 38 communicate with each of the blending receptacles 34 and extend out of

the tank, the outlet ends thereof being disposed substantially below the surface elevation of the water in the tank. Obviously, the cross sectional size of these tubes 38 is necessarily several-fold larger than the largest of the pieces of heavy materials to be carried thereby. The difference of head of the water between the surface elevation thereof in the tank and the end of the discharge tube 38 causes water to flow through the tube 38 and in close proximity with and through the heavy materials connected in blending receptacles 34. The water so flowing into and through tube 38 carries the heavy material collected in the blending receptacles 34 along with it through the tube 38 to be discharged outside of the tank.

Both water and solid material flow through both the siphon tubes 30 and the heavy material discharge tubes 38. The form of my invention shown includes suitable means, such as a screen or filter 39, onto which is discharged the solid materials and water from the siphon tubes and discharge tubes. The water passes through screen 39 into a vessel 40. The solid materials are retained by the screen and will slide therefrom to be collected for use or disposal as the case may be. A separate section of the screen is provided to receive the discharge from each of the siphon tubes 30 and the discharge tubes 38. Substantially all of the abrasive materials are removed from the water by the screen 39.

The water from which the solids have been removed is collected in the vessel 40, by means of a hydraulic pump 41 through pipes 42 and is recirculated back to tank 10. Pump 41, and pipes 42, are of such size as to be able to carry the full water discharge of all the siphon tubes and discharge tubes from the tank 10 to the screens 39. The pump 41 need not be of any special type because it pumps merely the water from which substantially all the abrasive solid materials have been removed by means of the screens 39.

It will be apparent from the foregoing description that my new method for separating gravel and the like from lighter foreign materials mixed therewith consists in the following specific steps:

Substantially horizontally confining and submerging the mixture of gravel and lighter materials in a liquid; moving the mixture through the liquid and simultaneously shaking the same to accumulate the lighter materials of the mixture into an upper layer disposed above a lower layer of heavier material, such as the gravel; and collecting and discharge the layer of lighter materials by siphon action.

My new method may also include the following additional specific steps:

Separating the water from the solids carried thereby and collecting the water; pumping the solid-free water thus collected back into the separating system to recirculate the same.

It will be seen that I have provided a simple and easily manufactured gravity-type separator for gravel and the like. Its initial cost is comparatively low in that the use of siphon tubes for carrying abrasive material has eliminated the need for expensive abrasive propelling pumps.

It should also be noted that I have provided in my separating apparatus oscillating material-carrying beds which not only separate the lighter of the materials from the heavier materials, but also circulate water around the materials in a severe scrubbing action and cause them to be cleansed as they pass along the bed.

I also provide a drain pipe 43 in the bottom of tank 10 for carrying the sediment that will be collected there as the water circulates through and scrubs the gravel in the beds 14, said and other sediment will be freed. This sediment will collect in the bottom of the tank 10 and must be removed. A drain pipe 43 communicates with the bottom of the tank 10 to carry off the sediment collected. The drain pipe 43 may have a valve 44 therein to control the flow of water in the pipe. If suf-

ficient head room is available, the bottom of the tank 10 should be funnel-shaped and the drain pipe should extend from the vertex of the funnel-shaped bottom. Such a funnel-shaped bottom will provide for more efficient disposal of sediment. I also provide a drain pipe 45 which communicates with the bottom of tank 40 for disposing of any sediment that may be collected therein. Drain pipe 45 may have a cooperating valve 46 for controlling the flow therethrough.

It will be seen that I have provided a new and highly novel apparatus for separating materials having different specific gravities. My submerged-type separating apparatus removes and discharges the lighter materials by use of siphon tubes. The use of siphon tubes entirely eliminates pumping of abrasives. In that the discharging abrasive materials move slower in the siphon tubes than it would in pumps, there is comparatively less wearing of the siphon tubes and requires only an absolute minimum of maintainance expense for my apparatus.

It should be obvious that, for a constant water level in the tank, the rate of flow through the siphon tubes will be substantially constant. The only variable that would tend to vary the flow is the friction between the moving solids and the siphon tubes. When the solids are suspended, and carried by turbulent water, this friction does not substantially change.

It should also be noted that I have provided in my apparatus for the delivery of all of the solids and water onto screens. The water is here separated from substantially all of the abrasive materials and then collected in a container disposed below the screens. The water is then recirculated back into the gravity separator by means of a single pump. This is the only pump used in my entire system and it pumps only water which is substantially free of abrasive materials.

It is also apparent that I have provided in my apparatus for accurate proportioning and blending of various quantities of cleaned gravel into mixtures which meet rigid blending specifications. The gravel discharged from my apparatus is therefore ready for sale and use.

It will, of course, be understood that various changes may be made in the form, detail, arrangement and proportion of the parts without departing from the scope of my invention.

What I claim is:

1. In a gravity separator of the submerged type being particularly adapted for cleaning and classifying gravel and the like which is mixed with other materials having various specific gravities, the combination of a liquid-confining tank; means for maintaining a liquid level in said tank; a number of separation beds shiftably mounted in said tank below the liquid level therein for oscillatory movement; supply means for delivering such a mixture of materials to said beds; an oscillator connected to said beds to cause the mixed materials therein to move from the ingress ends toward the egress ends of said beds and to cause the lighter materials of the mixture to rise in a layer above the heavier materials; a number of material-carrying conduits for respectively discharging the layer of light materials from each of said beds, each of said conduits extending out of the tank and having its inlet end adjacent to the egress end of a bed and in spaced relation above the bottom thereof and having its outlet end disposed substantially below the liquid level in the tank, whereby the head of the liquid between the surface of the liquid and the outlet end of the conduit causes liquid to flow turbulently in close proximity with and through the layer of light material and into and through said discharge conduit, and whereby the flowing liquid carries the light materials with it; the heavy materials continuing to move in the bed toward the agress end thereof; and means for collecting the heavy materials from the respective beds and discharging the same to without the tank.

2. In a gravity separator of the submerged type being particularly adapted for cleaning and classifying gravel and the like, the combination of a liquid-confining tank; means for maintaining a liquid level in said tank; a number of separation beds shiftably mounted in said tank and being submerged below the liquid level therein; supply means for delivering a mixture of materials to said submerged beds, the materials having various specific gravities; an oscillator connected to said beds to cause the mixed material therein to move from the ingress ends toward the egress ends of said beds and to cause the lighter material of the mixture to rise in a layer above the heavier material; a number of siphon tubes each having its inlet end adjacent the egress end of a corresponding bed and in spaced relation above the bottom thereof, whereby said tube will remove and discharge the layer of light material from the layer of heavy material being disposed therebelow; the heavy materials continuing to move toward the egress end of the beds, and means for collecting and discharging the heavy materials from the respective beds to without the tank.
3. In a gravity separator of the submerged type being particularly adapted for cleaning and classifying gravel and the like, the combination of a liquid-confining tank; a liquid supply for said tank having valve means for maintaining a liquid level in said tank; a number of shallow, open top, separating trays shiftably mounted in said tank and submerged below the liquid level therein; supply means for delivering a mixture of materials having various specific gravities to one end of each of said submerged trays; an oscillator connected to said trays to cause the mixed materials to move from the ingress ends toward the egress ends of said trays and to cause the lighter material of the mixture to rise in a layer above the heavier material; a number of siphon tubes each having its inlet end adjacent the egress end of a corresponding tray and in spaced relation above the bottom thereof and being adapted to remove the layer of light material from the layer of heavy material disposed therebelow; the heavy material continuing to move toward the egress end of the tray, and means for collecting and discharging the heavy materials from the respective trays to without the tank.
4. In a gravity separator of the submerged type being particularly adapted for cleaning and classifying gravel and the like, the combination of a liquid-confining tank; a liquid supply, means for carrying liquid from said supply into said tank and having valve means for maintaining a liquid level in said tank; a number of open-topped, shallow separating trays shiftably mounted in said tank below the liquid level therein; supply means for delivering a mixture of materials having various specific gravities to one end of each of said trays; a mechanical oscillator connected to said trays to cause the mixed materials to move from the ingress ends toward the egress ends of said trays, and to cause the lighter materials of the mixture to rise in a layer above the heavier materials; a number of siphon tubes extending into and out of said tank for removing the layer of light material from the layer of heavier material disposed therebelow in said trays, said tubes each having flow regulating valve mechanism therein and having its inlet end adjacent the egress end of a corresponding tray and in spaced relation above the bottom thereof; the heavy material continuing to move toward the egress end of the trays and being spilled thereover, means for collecting and discharging the heavy material spilled over the egress end of said oscillating separation trays; filters for receiving the wet agglomerate from the siphon tubes and for retaining the solid materials and passing the liquid; a liquid-receiving vessel disposed below said filter for collecting the liquid therefrom; and a pump for recirculating liquid collected after the same had

substantially all the abrasive materials removed therefrom.

5. In a gravity-type separator of the submerged type being particularly adapted for cleaning and classifying gravel and the like, the combination of a liquid-confining tank; means for maintaining a liquid level in said tank; a plurality of perforate, material-carrying and separating trays being horizontally disposed and vertically spaced and being shiftably mounted in said tank below the liquid level therein; supply means for delivering a mixture of materials having various specific gravities to one end of each of said trays; an oscillator connected to said trays to cause the mixed materials to move from the ingress ends toward the egress ends of said trays and to cause the lighter materials of the mixture to rise in a layer above the heavier mixture; a number of siphon tubes for removing the layer of light materials from the layer of heavier materials being disposed therebelow, each of said tubes having flow-regulating means therein and each having an inlet housing having an elongated opening therein extending laterally of a tray and substantially across the width of the tray, said opening being adjacent the egress end of the corresponding tray and in spaced relation above the bottom thereof; heavy material collectors being disposed adjacent and below the egress ends of the trays; means operatively associated with said collectors for discharging the heavy materials to without the tank; and means associated with said heavy material collectors for proportioning and blending predetermined quantities of the various size-graded heavy materials.

6. In a gravity separator of the submerged type being particularly adapted for cleaning and classifying gravel and the like, the combination of a liquid-confining tank; means for maintaining a liquid level in said tank; a number of vertically spaced, open-top, substantially rectangular separating trays being shiftably mounted in said tank below the liquid level therein; supply means for delivering a mixture of materials having various specific gravities to one end of each of said trays; a powered oscillator connected to said trays causing a reciprocating movement of said trays in a vertical direction and a direction longitudinal of the trays, whereby the mixed materials are caused to move from the ingress ends toward the egress ends of said trays; and whereby the mixture of materials stratifies with the lighter materials rising above the heavier materials; a number of siphon tubes to remove the layer of lighter materials from the trays, each of said siphon tubes having an elongated slot formed in its inlet end and extending transversely of a tray and substantially across the width of the same, said slot being disposed in spaced relation above the bottom of the tray and adjacent the egress end thereof; the heavy material continuing to move past the inlet end of the suction tube toward the egress end of the trays and being spilled thereover; collecting hoppers, one being disposed adjacent and below the egress end of each of said trays for receiving heavy materials spilled from said trays; blending receptacles being disposed below said hoppers; conveying means connecting each of said hoppers to various blending receptacles; material proportioning means mounted in each of said hoppers for proportioning the heavy materials spilling therein; and directing the same into a blending receptacle; means

65

operatively associated with said blending receptacles for collecting and discharging the blended heavy materials; means for separating and collecting the liquid discharged with said materials; and a pump for recirculating liquid collected after the same has had substantially all the abrasive materials removed therefrom.

7. In a gravity separator of the submerged type being particularly adapted for cleaning and classifying gravel and the like which is mixed with other materials having various specific gravities, the combination of a liquid-confining tank; means for maintaining a liquid level in said tank; a separation bed shiftably mounted in said tank below the liquid level therein for oscillatory movement; supply means for delivering such a mixture of materials to said bed; an oscillator connected to said bed to cause the mixed material therein to move from the ingress end toward the egress end of the bed and to cause the lighter materials of the mixture to rise in a layer above the heavier materials; a material-carrying suction housing spaced inwardly from the egress end of the bed and having a suction inlet disposed below the liquid level in the tank and in spaced relation above the bottom of the bed; means producing suction pressure in said suction housing and discharging liquid and light weight materials to without the tank, whereby the materials commence stratification as they move from the ingress end of the bed and the upper light material layer is removed through the suction housing; and means for collecting the heavy materials from the bed and discharging the same to without the tank.

8. In a gravity separator of the submerged type being particularly adapted for cleaning and classifying gravel and the like which is mixed with other materials having various specific gravities, the combination of a liquid-confining tank; means for maintaining a liquid level in said tank; a separation bed shiftably mounted in said tank below the liquid level therein for oscillatory movement; supply means for delivering such a mixture of materials to said bed; an oscillator connected to said bed to cause the mixed materials therein to move from the ingress end toward the egress end of said bed and to cause the lighter materials of the mixture to rise in a layer above the heavier materials; a material-carrying conduit for discharging the layer of light material from said bed, said conduit extending out of the tank and having its inlet end inwardly from the egress end of the bed and in spaced relation above the bottom thereof and having its outlet end disposed substantially below the liquid level in the tank, whereby the head of liquid between the surface of the liquid and the outlet end of the conduit causes liquid to flow turbulently in close proximity with and through the layer of light material and into and through said discharge conduit, and whereby the flowing liquid carries the light materials with it; the heavy materials continuing to move in the bed toward the egress end thereof; and means for collecting the heavy materials from the bed and discharging the same to without the tank.
